UNITED STATES PATENT OFFICE.

JOHN C. METTLER, OF CHICAGO, ILLINOIS, ASSIGNOR TO BEARDSLEE CHANDELIER MANUFACTURING COMPANY, OF CHICAGO, ILLINOIS, A CORPORATION OF DELAWARE.

DESIGN FOR A PLATE FOR LIGHTING FIXTURES.

Application filed April 23, 1924. Serial No. 9,363. Term of patent 7 years.

To all whom it may concern:

Be it known that I, JOHN C. METTLER, a citizen of the United States, residing at Chicago, in the county of Cook and State of Illinois, have invented a new, original, and ornamental Design for Plate for Lighting Fixtures, of which the following is a specification, reference being had to the accompanying drawing, which forms a part hereof.

My invention as illustrated relates more especially to a plate adapted to be employed as a bracket back for a wall type of lighting fixture.

In the drawing:

Figure 1 is an elevation of a plate showing my new design.

Figure 2 is a side elevation thereof.

I claim:

The ornamental design for a plate for lighting fixtures as shown.

JOHN C. METTLER.
